UNITED STATES PATENT OFFICE

JOHN A. ROBINSON, OF SAN DIEGO, CALIFORNIA

SUBMARINE SAFETY APPARATUS

Application filed July 23, 1930. Serial No. 470,011.

My invention relates to submarine safety devices, and the objects of my invention are:

First, to provide a device of this class which enables communication to be established and air to be supplied to persons trapped in a sunken submarine without requiring a diver to descend to the submarine;

Second, to provide a safety device of this class in which the apparatus used by the rescuing ship is simple enough that it can be carried on any vessel so that the first ship to the scene of the disaster may proceed with rescuing operations, thereby saving valuable time;

Third, to provide an apparatus of this class which does not interfere with the ordinary use of the submarine;

Fourth, to provide an apparatus of this class in which the portion thereof carried by the submarine is small and compact enough that one or more may be provided for each compartment;

Fifth, to provide an apparatus of this class in which a buoy may be raised to the surface from any compartment in which men are still alive, or may be arranged to rise automatically so as to mark the spot at which the submarine sank;

Sixth, to provide an apparatus of this class in which communication may be quickly established between the submarine and the rescuing vessel and the communication maintained during the operation of connecting the air supply hose to the submarine so that the most efficient cooperation may be had between the members of the submarine and the rescue vessel;

Seventh, to provide an apparatus of this class in which electric power as well as air and telephone facilities may be supplied so that if certain compartments of the submarine are intact, the crew may operate the machinery or tools to effect their own escape from the submarine, or facilitate the work of salvaging the submarine; and

Eighth, to provide an apparatus of this class which is particularly simple of construction proportional to its functions, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon, which form a part of this application, in which:

Figure 1 is a diagrammatical view showing a sunken submarine in sectional outline and illustrating the means of effecting a rescue; Fig. 2 is a sectional view of the apparatus as installed on the submarine ready for use in case of disaster; Fig. 3 is a similar fragmentary sectional view showing the air supply hose connected ready to supply air to the sunken submarine; Fig. 4 is another similar sectional view showing a further step in the rescue operation, in which air is being supplied to the men in the submarine; Fig. 5 is a plan view of the float and its receiving cradle, under normal conditions; Fig. 6 is a fragmentary sectional view substantially through 6—6 of Fig. 5; Fig. 7 is an enlarged fragmentary sectional view of the cable drum and its casing, showing means for maintaining a contact with electric wires carried by the buoy cable; Fig. 8 is an end elevational view of the contact rings and their insulated supports, taken substantially through 8—8 of Fig. 7; and Fig. 9 is a sectional view thereof through 9—9 of Fig. 7; Fig. 10 is an enlarged fragmentary elevational view of the other side of the cable drum casing, showing a means for locking the drum in any desired position; Fig. 11 is an enlarged fragmentary sectional view of the nozzle for the rescuing hose, showing a means for attaching it to the buoy cable so as to maintain communication between the submarine and the rescuing vessel; Fig. 12 is an enlarged fragmentary sectional view of the buoy, and illustrating the means of connecting it to the buoy cable; and Fig. 13 is a plan view of the coupling member for connecting the buoy cable to the buoy.

Similar characters of reference refer to similar parts and portions throughout the several views of the drawings.

Buoy cradle 1, cradle stem 2, guide rollers 3, roller guard 4, cable drum casing 5, air cock 6, coupling member 7, water discharge pipe 8, valve 9, cable drum 10, buoy cable 11, 5 ratchet means 12, locking lever 13, hand wheel 14, plug member 15, contact rings 16, conductor bars 17, sealing material 18, cap member 19, contact support 20, contacts 21, buoy cable fitting 22, beacon light cable fitting 23, beacon light cable 24, casing member 25, coupling members 26, buoy 27, beacon light 28, hose fitting 29, air supply hose 30, continuation cable fitting 31, continuation cable 32, locking screw 33, and inner air hose 34 constitute the principal parts and portions 10 of my submarine safety devices.

A buoy cradle is provided which is mounted in the space between the super-structure A and the hull B of the submarine. The 20 cradle is substantially funnel-shaped with a depending stem 2, having a tapered bore 2a corresponding to the spout of the funnel. The stem 2 is screw-threaded through an internally threaded boss B1 of the hull, forming 25 a water-tight joint therewith.

The buoy cradle 1 is circular in cross section, and has its largest diameter at its upper end, which is substantially flush with the super-structure A. Arranged around the rim 30 of the buoy cradle 1 are rollers 3, which are supported and separated by bearing portions 1a of the cradle.

Mounted on the structure A around the buoy cradle 1 is a guard ring 4 having finger 35 portions 4a, which extend over the spaces between the several rollers 3, as shown best in Figs. 2, 5, and 6. The purpose of the rollers and the guard ring will be brought out in more detail hereinafter.

40 The stem 2 extends into the hull of the submarine, and is secured to an internally threaded boss 5a of a cable drum casing 5. The casing 5 is cylindrical with its axis extending at right angles and in offset relation 45 to the boss 5a and axis of the stem 2, as shown best in Figs. 2 and 3.

At a suitable place at the lower side of the drum casing 5, there is provided an air cock 6, the function of which will be described in 50 more detail hereinafter.

Also at the lower side of the drum casing 5, there is provided a nipple 5b which is adapted to be connected by means of a coupling 7 to a water discharge pipe 8. The water discharge pipe 8 curves upwardly and opens to the outside of the hull, being connected to a fitting B2 provided in said hull. Somewhere in the length of the water discharge pipe 8, there is provided a valve 9.

60 Mounted in the cable drum casing 5, is a cable drum 10, comprising a hub portion 10a, and annular retaining flanges 10b arranged adjacent and inside of the ends of the casing 5.

65 Wound around the drum 10, is a buoy cable

11. The cable 11 performs two functions, one to effect operation of the buoy and rescuing apparatus, and the other to carry wires for establishing communication between the submarine and rescuing vessel or supply 70 power to the submarine from said vessel or current for lighting beacon lights provided with the buoy, to be described in more detail hereinafter.

The ends of the hub 10a extend through 75 packing glands 5c at the ends of the housing. The one protruding end of the hub 10a is provided with a ratchet wheel 12, which is adapted to be engaged by a locking lever 13 supported on the outside of the drum casing 5, as shown in Fig. 10. This end of the hub 10a is arranged to receive a hand wheel 14.

The other end of the hub 10a is provided with a recess or socket 10c therein, which receives a plug member 15 formed of insulating 80 material. Supported at the extended end of the plug member are a plurality of contact rings 16, which are connected to conductor bars 17, which extend through the plug member 15. The inner end of the plug 15 is spaced 90 slightly from the inner end of the socket 10c forming a chamber in which is fed the secured end 11a of the buoy cable 11. Electric wires 11b which are carried by the cable 11 are connected to the several conductor bars 17. 95 This space is then filled with a sealing material 18, as shown in Fig. 7.

Supported over this extended end of the hub 10a, is a cap member 19, in which is 100 mounted a contact support 20, upon which are mounted a plurality of contacts 21, adapted to make contact with the several contact rings 16. The cap member is prevented from rotating by means of suitable foot 19a extending from the cap member to the casing 5. 105

The cable 11, after winding around the drum, passes out through the boss 5a into the stem 2. The extended end of the cable 11 is provided with a cable fitting 22, shown best in Figs. 11, 12, and 13. This fitting is 110 provided with either contacting sockets or projections 22a which fit in complementary portions of a beacon light cable fitting 23 at the end of a beacon light cable 24. These members are held in secured relation by a casing 115 or shell member 25, which may screw on screw-threads provided on the outside of the fitting 22. The fitting 22 is larger than the diameter of the cable 11 forming a shoulder 22b.

The cable is secured to the buoy or to a rescue or air supply hose by means of a pair of coupling members 26. These members complement each other so as to form a bearing portion 26a, adapted to fit around the 125 cable 11 adjacent the fitting 22. This collar or bearing is connected by diverging webs 26b to a threaded ring portion 26c of larger diameter adapted to screw in a socket 27a provided in the under side of the buoy 27 and 130

form a water-tight seal therewith. Thus, the coupling members 26 together form a substantially conical shaped end piece having openings 26a between the webs 26b.

5 The buoy 27 is made spherical and strong enough to stand pressures at a considerable depth. The buoy light cable 24 extends upwardly through a packing gland 27b provided in the center of the socket 27a, and connects with a buoy light 28 mounted at the upper side of the buoy, as shown best in Figs. 2 and 5. This light may be protected by a suitable guard 27c.

When the coupling members are in place 15 in the socket 27a, they are held from spreading so that they are firmly though swivelly connected to the cable 11. By unscrewing these members from the buoy, they may be separated so as to release the cable 11.

20 The same coupling members or similar coupling members 26 may be used to connect the cable 11 to the end fitting 29 of an air supply hose 30. The fitting 29 is substantially in the form of a truncated cone, the side 25 wall converging gradually towards the extended end of the fitting. The lower end of the fitting 29 is internally threaded to receive ring portions 26c. The coupling members 26 together form a substantially conical 30 tip to the hose fitting 29 from the apex of which extends the cable 11, as shown best in Fig. 11.

The fitting 22 of the cable 11 is adapted to be secured to a fitting 31 of a continuation 35 cable 32. Said fitting 31 and cable 32 may be identical in construction to the beacon light cable fitting 33 and beacon light cable 24. The cable 32 extends within the air supply 40 hose 30 and is connected with a suitable telephone system on the rescuing vessel or with a source of electric supply or both, depending upon the number of wires carried.

Just above the lower end of the fitting 22, 45 there is provided an annular channel 29a of V-shaped cross section. The lower wall 29b, that is, the wall adjacent the extended end of the fitting 29, is adapted to be engaged by a locking screw 33, which is mounted in the 50 side wall of the stem 22 so as to force and hold the fitting 29 in the position shown in Fig. 3.

Operation of my submarine rescue apparatus is as follows:

55 The apparatus carried by the submarine is normally in the position shown in Fig. 2, the buoy 27 being held in the cradle 1 by the cable 11 which in turn is held by the drum 10, the drum being locked against rotation by the locking lever 13. With this normal condition, the valves 6 and 9 are closed while the discharge pipe 8 is connected to the drum casing.

60 It is preferred to provide one or more of

these apparatus in each compartment of the submarine.

When the submarine sinks by accident, any man remaining alive in any compartment releases the lever 13 allowing the buoy to rise 70 to the surface of the water. This movement is assisted by turning the handle wheel 14 which controls the drum so that a relatively small buoy may be used for this purpose. If the electric supply of the submarine is still 75 available it may be connected with several of the wires from the contact 21 so as to light the beacon 28. As soon as the rescue ship reaches the spot the buoy is lifted aboard 80 ship, there being provided enough extra cable on the drum, under most circumstances, to permit this.

On the rescue ship, the buoy is removed and the cable 11 is joined to the rescue or air supply hose 30, through the coupling 29. At 85 the same time, the connection is made with the continuing cable 32, which establishes communication between the rescue ship and the submarine.

The members of the submarine crew then 90 rotate the drum by means of a hand wheel 14, drawing the air supply hose to the submarine.

Should the submarine be listing, the rollers and guard ring function to prevent the supply 95 hose from catching.

As both the bore of the stem 2 and the walls of the hose fitting 29 are tapered, the hose fitting may be drawn into snug relation with the fitting 2 by the cable 11. When this is done, a locking screw 33 is turned so as to cause the point thereof to bear against the lower slope 29b of the annular channel 29a provided in the fitting 29, as shown in Fig. 3. This holds the fitting firmly in place in the 100 stem 2.

After this is done, the submarine notifies the rescue ship of the fact and water which has filled in the air supply pipe during its descent to the submarine is blown out the discharge pipe 8, the valve 9 being open. The 105 hose is purposely allowed to fill with water so that it can more readily be pulled down to the submarine; otherwise, considerable force would be required to overcome the buoyancy 110 of air in the air supply line.

When all the water has been blown out, and air begins to come, the valve 9 is closed and the air cock 6 is open, permitting the passage 115 of air into the compartment of the submarine. When this is done, the coupling 7 is unscrewed from the casing 5, and the casing 5 is disconnected from the stem 2. The joint between the cable 11 and the coupling members 26 permits rotation of the casing 5. After this 120 is accomplished, the coupling members 26 may be removed so that in addition to the supply hose 30, a second smaller pipe 34 may be passed down the inside thereof, as shown in Fig. 4, for passing food in liquid form, or 125

permitting a return flow of air so as to keep a fresh supply in the submarine.

At all times, communication may be maintained through the cable 11 and the continuing cable 32. Thus, the crew of the rescue ship 5 may cooperate with the members of the submarine crew and thereby facilitate salvaging on the submarine as well as saving the lives of the crew.

10 If the supply hose is reinforced so as to withstand the pressure of the water, once it is connected to the submarine and the water therein has been discharged, the upper end of the supply hose may be disconnected from the 15 compressor and be open to the atmosphere. In such case, the inner hose 34 alone may supply the fresh air.

In certain compartments of the submarine, where space permits, the stem 2, pipe fitting 20 29, and coupling members 26 used in connection therewith may be enlarged so as to connect with a tube large enough to permit a man to pass through. This tube is vented to the atmosphere and is reinforced so as to withstand the water pressure. Much of the remaining mechanism need not be greatly enlarged as the cable 11 need only be used to 25 guide the tube to the submarine, the tube being open at its lower end so as to at first fill 30 with water.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

40 Having thus described my invention, what I claim as new and desire to secure by Letters Patent is:

1. In a submarine safety apparatus, a housing mounted within a submarine and having 45 a passage communicating with the exterior of said submarine, a cable drum rotatably mounted in said housing, a cable wrapped around said cable drum and extending through said passage, a buoy securable to the 50 extended end of said cable arranged to lift said cable to the surface of the water, an air supply hose, means for attaching said cable to said air supply hose, and means operable from within said submarine for re-winding 55 said cable and drawing said air supply hose to said submarine.

2. In a submarine safety apparatus, a cable drum mounted within the hull of a submarine, a casing therefor having a passage communicating with the exterior of said submarine, a cable wrapped around said drum, the one end thereof projecting through said passage, a buoy, coupling means for connecting said cable to said buoy, an air supply 65 conduit carried by a rescuing vessel, means

for attaching said cable to said air supply conduit, means for re-winding said cable, and a fitting for said air supply conduit for forming a sealed joint between said passage and said air supply conduit.

3. In a submarine rescue apparatus, a casing mounted within the hull of a submarine, said casing provided with an open passage 70 communicating with the exterior of said hull, and a valve controlled passage communicating with the interior of said hull, a cable drum rotatably mounted in said casing, a cable therefor extending through said first-mentioned passage, a buoy for said cable, a supply conduit for said cable, coupling means for connecting said cable to said buoy or to said supply conduit, a fitting for said supply conduit, and means for rewinding said cable for drawing said fitting into sealed relation with said first-mentioned passage.

4. In a submarine safety apparatus, a casing, provided with an open passage communicating with the exterior of a submarine, a second passage communicating with the interior of said submarine, a valve for controlling said second passage, a drum mounted in said casing, a cable for said drum, means for raising said cable to the surface of the water, a supply conduit, coupling means for connecting said cable to said supply conduit, and means for re-winding said cable so as to draw the end of said supply conduit into said first-mentioned passage.

5. In a submarine safety apparatus, the combination with a submarine and a rescue vessel, of a cable carried by said submarine, a buoy for raising an end of said cable to the surface of the water, means operable from within said submarine for drawing said cable back, a tube carried by said rescue vessel, and coupling means for connecting said cable to said tube.

6. In a submarine safety apparatus, the combination with a submarine and a rescue vessel, of a cable carried by said submarine, 110 a buoy for raising an end of said cable to the surface of the water, means operable from within said submarine for drawing said cable back, a tube carried by said rescue vessel, coupling means for connecting said cable to 115 said tube, a fitting at the end of said tube, and a corresponding fitting on said submarine, said cable arranged to draw said fittings into sealed relation.

7. In a submarine safety apparatus, the combination with a submarine and a rescue vessel, of a cable carried by said submarine, a buoy for raising an end of said cable to the surface of the water, means operable from within said submarine for drawing said cable back, a tube carried by said rescue vessel, coupling means for connecting said cable to 120 said tube, an open ended fitting at the end of said tube whereby said tube fills with water during descent to said submarine, a 125

corresponding fitting on said submarine, said cable arranged to draw said fittings into sealed relation, and bypass means for conducting water entrapped in said tube back into the water surrounding said submarine upon the filling of said tube with air.

5 8. In a submarine safety apparatus, the combination with a submarine and a rescue vessel, of a cable carried by said submarine, a buoy for raising an end of said cable to the surface of the water, means operable from within said submarine for drawing said cable back, a tube carried by said rescue vessel, coupling means for connecting said cable to said tube, and means carried by said cable and said tube for establishing electrical communication between said submarine and said rescue vessel.

10 9. In a submarine safety apparatus, the combination with a submarine and a rescue vessel, of a cable carried by said submarine, a buoy for raising an end of said cable to the surface of the water, means operable from within said submarine for drawing said cable back, a tube carried by said rescue vessel, coupling means for connecting said cable to said tube, a fitting at the end of said tube, a corresponding fitting on said submarine, said cable arranged to draw said fittings into sealed relation, and means carried by said cable and said air supply conduit for establishing electrical communication between said submarine and said rescue vessel.

15 10. In a submarine safety apparatus, the combination with a submarine and a rescue vessel, of a cable carried by said submarine, a buoy for raising an end of said cable to the surface of the water, means operable from within said submarine for drawing said cable back, a tube carried by said rescue vessel, coupling means for connecting said cable to said tube, an electric line carried by said cable, a beacon light carried by said buoy, and electric wires carried by said tube, said electric line connectible to either said beacon light or said electric wires.

20 11. In a submarine safety apparatus, the combination with a submarine and a rescue vessel, of a cable carried by said submarine, a buoy for raising an end of said cable to the surface of the water, means operable from within said submarine for drawing said cable back, a tube carried by said rescue vessel, coupling means for connecting said cable to said tube, a fitting at the end of said tube, a corresponding fitting on said submarine, said cable arranged to draw said fittings on said submarine, an electric line carried by said cable, a beacon light carried by said buoy, and electric wires carried by said air supply conduit, said electric line connectible to either said beacon light or said electric wires.

25 12. In a submarine safety apparatus, the combination with a submarine and a rescue

vessel, of a cable carried by said submarine, a buoy for raising an end of said cable to the surface of the water, means operable from within said submarine for drawing said cable back, a tube carried by said rescue vessel, coupling means for connecting said cable to said tube, an open ended fitting at the end of said tube whereby said tube fills with water during descent to said submarine, a corresponding fitting on said submarine, said cable arranged to draw said fittings into sealed relation, bypass means for conducting water entrapped in said tube back into the water surrounding said submarine upon the filling of said tube with air, an electric line carried by said cable, a beacon light carried by said buoy, and electric wires carried by said air supply conduit, said electric line connectible to either said beacon light or said electric wires.

30 13. In a submarine safety apparatus, the combination with a submarine and a rescue vessel, of a cable carried by said submarine, a buoy for raising an end of said cable to the surface of the water, means operable from within said submarine for drawing said cable back, a tube carried by said rescue vessel, coupling means for connecting said cable to said tube, a fitting at the end of said tube, a corresponding fitting on said submarine, said cable arranged to draw said fittings into sealed relation, and an inner air hose carried by said tube, whereby air may pass into said submarine from said inner air hose and out therefrom through said tube.

35 14. In a submarine safety apparatus, the combination with a submarine and a rescue vessel, of a cable carried by said submarine, a buoy for raising an end of said cable to the surface of the water, means operable from within said submarine for drawing said cable back, a tube carried by said rescue vessel, coupling means for connecting said cable to said tube, an open ended fitting at the end of said tube whereby said tube fills with water during descent to said submarine, a corresponding fitting on said submarine, said cable arranged to draw said fittings into sealed relation, by pass means for conducting water entrapped in said tube back into the water surrounding said submarine upon the filling of said tube with air, and an inner air hose carried by said tube, whereby air may pass into said submarine from said inner air hose and out therefrom through said tube.

40 15. In a submarine safety apparatus, the combination with a submarine and a rescue vessel, of a cable carried by said submarine, a buoy for raising an end of said cable to the surface of the water, means operable from within said submarine for drawing said cable back, a tube carried by said rescue vessel, coupling means for connecting said cable to said tube, a fitting at the end of said tube, a corresponding fitting on said submarine, said cable arranged to draw said fittings into

sealed relation, means carried by said cable and said air supply conduit for establishing electrical communication between said submarine and said rescue vessel, and an inner air hose carried by said tube, whereby air 5 may pass into said submarine from said inner air hose and out therefrom through said tube.

16. In a submarine safety apparatus, the 10 combination with a submarine and a rescue vessel, of a cable carried by said submarine, a buoy for raising an end of said cable to the surface of the water, means operable from within said submarine for drawing said cable 15 back, a tube carried by said rescue vessel, coupling means for connecting said cable to said tube, a fitting at the end of said tube, a corresponding fitting on said submarine, said cable arranged to draw said fittings on 20 said submarine, an electric line carried by said cable, a beacon light carried by said buoy, and electric wires carried by said air supply conduit, said electric line connectible to either said beacon light or said electric 25 wires, and an inner air hose carried by said tube, whereby air may pass into said submarine from said inner air hose and out therefrom through said tube.

17. In a submarine safety apparatus, a 30 casing, provided with an open passage communicating with the exterior of a submarine, a second passage communicating with the interior of said submarine, a valve for controlling said second passage, a buoy cradle arranged over the outlet end of said first passage, a drum mounted in said casing, a cable for said drum, a buoy normally supported in said buoy cradle coupled to said cable and arranged to raise said cable to the surface of 35 the water, a tube carried by a rescue ship, said cable connectible to said tube, means for rewinding said cable so as to draw the end of said tube to said first mentioned passage, and guide means around the inlet to said 40 buoy cradle.

In testimony whereof, I have hereunto set my hand at San Diego, California, this 16th day of July, 1930.

JOHN A. ROBINSON.
